KNOCKDOWN CARRIER CARTON

John O. Grady, Arab, Ala.

Application September 15, 1943, Serial No. 502,516

6 Claims. (Cl. 224—48)

1

This invention relates to portable receptacles used for carrying articles from place to place and more particularly to a knockdown carrier carton.

It is an object of the invention to provide a container or receptacle in the nature of a portable structure which may be readily assembled for use as a luggage carrier or a portable device for carrying bottles, jars, packages or other articles, or may be used as a magazine rack in the home or other desired location, or if for any reason it becomes desirable the device can be collapsed or knocked down to occupy a very small space in comparison with the space occupied when it is assembled.

A further object of the invention is to provide a device of the above character of few parts, of simple, inexpensive and durable construction as well as one easy to assemble or knock down.

The foregoing and other objects and advantages of the invention will become readily apparent in view of the following description taken in conjunction with the drawings, wherein:

Figure 1 is a side elevation illustrating one application of the invention;

Fig. 2, a section on the line 2—2 of Fig. 1;

Fig. 3, a section on the line 3—3 of Fig. 1;

Fig. 4, a longitudinal, vertical, section;

Fig. 5, a perspective of one of the side members; and

Fig. 6, a perspective of the bottom member.

Referring to the drawing wherein like characters of reference indicate like parts, the invention, as illustrated in the drawings, consists of only six individual members which when assembled form a portable carrier or article receptacle or basket having a handle or handgrip by means of which the device may be transported, all of the members being of light weight and of simple configuration to enable the most unskilled to assemble the device with minimum effort.

The device consists of a pair of end members 10, of identical construction, each having in its lower portion an opening 11 with a horizontal surface 12 and feet 13, the extremities of which are in a plane parallel to the surface 12 so that a bottom 14 may be applied to the end members 10 and maintain the ends in definitely spaced relation as well as serve as a bottom for the receptacle. The bottom 14 may be provided with slots 31 which may be varied to suit.

In order to lock the ends in spaced relation adjacent their lower portions or legs the bottom at each end has T-shaped projections 15 so that the head of a T may be inserted through the openings 11 in one of the end members and then depressed so that the square portions 16 at one end of the

2

bottom engage the inner face or surface of one of the end members and the undersurface 17 of the T will engage the exterior face or surface of the corresponding end member and, due to the constrictions 18 in the end member which fit into the space between the surfaces 16 and 17, the end will be held fixed relative to the end of the bottom.

The end members 10 are provided with slots 19 for the reception of a handle 20 having ears 21 of a size to snugly fill the slots 19, it being necessary to insert the ears 21 into the slots 19 prior to the application of the bottom. The handle 20 may have a finger slot 22 to facilitate carrying the device.

So far there has been described a bottom, two ends and a carrying handle, the ends being maintained in spaced relation at their lower extremities and the top by the bottom and handle respectively. In order to more firmly lock these parts in the relation just described a pair of side members 23 are provided, each side member having square surfaces 24 and 25 at its ends and bottom for engagement with the ends and bottom of the device and therefore to form with each other and with the bottom and ends of the device a five-sided structure open at its top into which articles to be transported can be inserted. To assist in providing complementary locking together of the parts the end members have grooves 26 terminating at their upper extremities in slots 27 and the bottom is provided with substantially rectangular openings 28 for engagement by the sides 23.

The sides are placed in position and slid downwardly to final position with the ends 24 of the sides resting in the slots or grooves 26, the tongues 29 of the sides entering and substantially filling the rectangular openings 28 and the hook-like ears 30 extending through the slots 27 and hooking over the exterior outer surface of the end members 10.

Thus a rigid, sturdy, carrier of light weight is provided of simple, inexpensive and durable construction capable of being quickly and easily assembled and the parts being particularly susceptible of mass production.

In the above described process of assembling the two ends, the handle, the bottom and the two sides in that order is reversed in collapsing the device. As long as the sides 23 are in place the device is a rigid structure. Removal of the sides, the bottom and the handle accomplishes complete separation of the parts so that they may be placed compactly together in flat relation.

It will be obvious to those skilled in the art that various changes may be made in the invention

without departing from the spirit thereof, including among other things the configuration of the several parts where they do not come in contact with other members, certain of the configurations being designed with a utilitarian object.

What is claimed is:

1. A portable knockdown carrier carton comprising a pair of end members, a pair of side members, a bottom, and a handle, constructed to fit together and provide a rigid carrier receptacle, said end members having centrally located slots adjacent their upper extremities for reception of opposite ends of the handle and having openings adjacent their lower extremities with constricted lower portions through which openings the extremities of the bottom may be inserted and lowered into position between said constricted portions, the extremities of said bottom being T-shaped, the under surface of the top of the T engaging and limiting outward movement of said ends, said bottom also having flat surfaces spaced from the end surfaces of the T which flat surfaces engage the inner surfaces of the ends and prevent movement of the ends toward each other whereby the ends are held in relatively fixed relation and are prevented from moving in substantially parallel planes by the width of the legs of the T filling the constricted portions of the openings in the ends, said bottom having slots adjacent its sides and said ends having upright grooves located in the same relative positions as the slots in the bottom, and side members slidably disposed in said grooves and provided with tongues for engaging the slots in said bottom; said side members having locking ears at their upper corners extending beyond and hooking over and engaging the outer surface of the end members.

2. A portable knockdown carrier carton comprising end members, side members, a bottom, and a handle, constructed to fit together and provide a rigid carrier receptacle, said end members and said handle being formed to have interlocking engagement having openings adjacent their lower extremities with constricted lower portions through which openings the extremities of the bottom may be inserted and lowered into position between said constricted portions, the extremities of said bottom being T-shaped, the under surface of the top of the T engaging and limiting outward movement of said ends, said bottom also having flat surfaces spaced from the end surfaces of the T which flat surfaces engage the inner surfaces of the ends and prevent movement of the ends toward each other whereby the ends are held in relatively fixed relation and are prevented from moving in substantially parallel planes by the width of the legs of the T filling the constricted portions of the openings in the ends, said bottom having slots adjacent its sides and said ends having upright grooves located in the same relative positions as the slots in the bottom, and side members slidably disposed in said grooves and provided with tongues for engaging the slots in said bottom; said side members having locking ears at their upper corners extending beyond and hooking over and engaging the outer surface of the end members.

3. In a portable knockdown carrier carton end members, side members, a bottom, and a handle, constructed to fit together and provide a rigid carrier receptacle, said end members and said handle being formed to have interlocking engagement with the former having openings ad-

jacent their lower extremities with constricted lower portions through which openings the extremities of the bottom may be inserted and lowered into position between said constricted portions, the extremities of said bottom being T-shaped, the under surface of the top of the T engaging and limiting outward movement of said ends, said bottom also having flat surfaces spaced from the end surfaces of the T which flat surfaces engage the inner surfaces of the ends and prevent movement of the ends toward each other whereby the ends are held in relatively fixed relation and are prevented from moving in substantially parallel planes by the width of the legs of the T filling the constricted portions of the openings in the ends.

4. A portable knockdown carrier carton comprising end members, side members, a bottom and a handle, constructed to interlockingly fit together and provide a rigid carrier receptacle, said end members having slots adjacent their upper extremities for reception of the opposite ends of the handle, and having openings adjacent their lower extremities for interlocking reception of said bottom, said bottom having slots adjacent its sides and said ends having upright grooves located in the same relative positions as the slots in the bottom, and side members slidably disposed in said grooves and provided with tongues for engaging the slots in said bottom, said side members having locking ears at their upper corners extending beyond and hooking over and engaging the outer surface of the end members.

5. A portable knockdown carrier carton comprising end members, side members, a bottom and a handle constructed to interlockingly fit together and provide a rigid carrier receptacle, said end members having slots adjacent their upper extremities for interlocking reception of the opposite ends of the handle, and having openings adjacent their lower extremities for interlocking reception of said bottom, said bottom having slots adjacent its sides and said ends having upright grooves located in the same relative positions as the slots in the bottom, and side members slidably disposed in said grooves and provided with tongues for engaging the slots in said bottom.

6. A portable knockdown carrier carton comprising interlocking sides, ends, a bottom and a handle, said members characterized by the end members having vertical slots adjacent their tops and said handle having extending tongues adapted to be received in the vertical slots in the end members and lock therewith after insertion and positioning the end members vertically with respect to the handle, the lower portions of the end members having openings therethrough and the bottom member having lengthwise extending tongues for extending through said lower openings in the end members, locking elements on said tongues engageable with the outer sides of the end members when the bottom member is seated with the tongues engaging the bottom portion of said lower openings in the end members to thereby lock the end members with respect to the handle and bottom members, and side members having tongues extending lengthwise of the upper edge thereof and laterally downward from the lower edge thereof, said end members having slots extending downward from upper lateral portions thereof for locking engagement with the lengthwise extending tongues on the side member, and said bottom members hav-

ing slots for receiving the laterally downwardly extending tongues on said side members concurrently with the lengthwise extending tongues being positioned in locking engagement with the downwardly extending slots in the end members, and said end member also having grooves co-extensive with said downwardly extending slots therein for receiving the ends of the side members.
